PROCESS OF DRY SPINNING ARTIFICIAL THREAD

Robert M. Hoffman, Waynesboro, Va., assignor to
 E. I. du Pont de Nemours & Company, Wil-
 mington, Del., a corporation of Delaware

Application October 23, 1937, Serial No. 170,617

7 Claims. (Cl. 18—54)

The instant invention pertains to the dry spinning of threads, yarns, or the like having sharp variations in denier along their length.

Previous attempts to dry spin cellulose acetate or other cellulose derivative yarn of variable or uneven denier in order to simulate the novelty effect obtainable with natural or wild silk have been attended with an indifferent amount of success. The principal difficulty with the prior method of forming such materials has been that the size of the thickened portions and the abruptness of variation from the thin to the thick portions has not been sufficient to give the desired effects in the finished fabric. Regenerated cellulose and similar materials formed by extrusion of a coagulable solution such as viscose into a liquid coagulating bath have attained a variation of size, frequency and abruptness of variation that is eminently satisfactory. Hitherto, however, it has not been possible to attain similar results in products which are formed by dry spinning, such as cellulose acetate.

One object of the present invention is to furnish a variable denier cellulose derivative yarn, particularly cellulose acetate. Another object is to provide a relatively simple process of dry spinning variable denier yarn without causing frequent yarn breaks. Still another object is to provide a variable denier cellulose acetate yarn in which the variations are relatively large in size, abrupt, and preferably at random intervals.

These objects are accomplished in general by extruding a cellulose derivative solution such as cellulose acetate into a gaseous evaporating medium flowing countercurrently to the direction of extrusion and at the same time periodically varying the ratio of speed of extrusion to the speed at which the yarn is withdrawn from contact with said evaporating medium.

In the drawing, Figure 1 illustrates a side elevation, partly in cross-section, of an apparatus for performing the invention; Figure 2 is a section taken along the line 2—2 of Figure 1.

In carrying the invention into practice, a cellulose derivative spinning solution is extruded either upwardly or downwardly through a spinneret into an air current which is moving in the opposite direction. Preferably, however, the extrusion is in a downward direction. After the greater portion of the volatile solvent has evaporated, the resulting yarn is withdrawn continuously from the spinning cell at a rate which varies in relation to the rate of extrusion and then wound upon a suitable collecting device. The variation in ratio between the take-up speed and

the extrusion speed is secured either by keeping the extrusion speed constant and varying the take-up speed or by keeping the take-up speed constant and varying the extrusion speed or by combining both methods. In practice, it is preferred to apply the former procedure in that it entails the least number of changes to existing equipment. This may be effected by any of the known methods such, for example, as described in the patent to Picard and Oriol, No. 2,120,990, filed January 28, 1936. In any case, the draw-off should be so situated and spaced with respect to the extrusion orifice that it exerts on the yarn an irregularly varying pull extending to the plastic portion of the yarn in the spinning cell. Preferably, the mechanism designed to accomplish the variations is such that variation in denier is random both with respect to size and spacing of the thickened portions. This may be accomplished by means of the draw-off mechanism disclosed in the patent to Picard and Oriol, No. 2,120,990.

The variable draw-off which, in effect, causes alternate stretching and relaxing of the plastic portion of the cellulose acetate yarn in dry spinning, may be accomplished in almost any suitable fashion. For instance, the cellulose acetate yarn may be passed over a cylindrical roller, the rotational speed of which is changed at intervals and to amounts and for periods corresponding to the frequency, degree, and length of irregularity desired. Alternatively, cellulose acetate yarn may be passed over an elliptically or other irregularly shaped roller which varies the linear speed at which the yarn is withdrawn from the spinning cell, as in the Picard and Oriol application referred to above. If desired, such roller may be eccentrically mounted and may be caused to move bodily, for instance to and fro, either continuously or intermittently while rotating. As another alternative, the cellulose acetate yarn may be conducted over or around a rotating roller or drum having a diameter which varies along its length. In such case, a variable draw-off is secured by shifting the position of the yarn along the drum either by means of a shifting guide or by traversing the drum on an axially slideable shaft. For this purpose, the drum or roller may be any suitable shape such as a truncated cone. Finally, the variable draw-off may be secured by moving bars across the yarn path to lengthen the length of travel from the spinning cell to the wind-up. The last mentioned type is illustrated in the drawing.

The variation in yarn denier may also be ef-

fected by a constant draw-off in combination with a varying rate of extrusion which may be induced, for example, by production of pulsations in the delivery of the spinning solution to the spinneret, suitably actuated members such as diaphragms, pistons, or plungers being for this purpose caused to vibrate, reciprocate, or oscillate in contact with the spinning solution. Any suitable means such as cams or eccentrics may be used for actuating the pulsation device. Thus, diaphragms exposed on one side of the spinning solution may be caused to vibrate by pulsations transmitted through a fluid acting on their other side, a suitably actuated plunger being employed to produce the pulsations in the transmitting fluid. To secure optimum variations in pump or supply delivery and thereby optimum variation in yarn denier, it is important that the connecting pipe therefrom to the spinneret be short and of a rigid character so that the pulsation be not excessively damped prior to extrusion of the solution through the spinneret.

Regardless of how a varying ratio of extrusion speed to take-up speed is accomplished, it is essential for the securement of a sharp variation in denier that the flow of air or other gaseous evaporating medium in the spinning cell be directed countercurrent to the travel of the thread from the spinneret. In downward spinning, in view of the fact that gravity aids the travel of the thread in its direction of withdrawal, the velocity of countercurrent air flow should preferably be at least 60 yards per minute when the speed of withdrawal of the yarn is 100 yards per minute or more. Whatever the direction of extrusion, the speed of withdrawal should preferably average at least 100 yards per minute and the speed of counterflow at least 40 yards per minute. At higher withdrawal speeds, the velocity of counterflow should be somewhat higher. The counterflow should extend substantially the entire length of the spinning cell although beneficial effects are still obtained, provided the air flow is countercurrent to the travel of the yarn over at least the region wherein the yarn still remains in a plastic state. In general, with other conditions constant, the higher the ratio of velocity of counterflow to speed of extrusion, the sharper the variation in denier. The counterflow may be either a continuous stream or an intermittent flow of air. If intermittent, depending on the effect desired, the counterflow may be pulsating or may be definitely interrupted at intervals of shorter or longer duration. Likewise, the intermittent counterflow may be an in- or an out-of-phase synchronization with a variable delivery mechanism.

The drawing illustrates one type of apparatus designed to accomplish these results. An acetone solution of cellulose acetate from a supply pipe 1 is extruded through a spinneret 2 to produce a filamentary yarn 8 which is led downward through a spinning cell 4 to a guide 6 from which the thread is led out of the spinning cell through the aperture 7. At the bottom of the spinning cell 4, air is introduced through the opening 5 and passed upwardly through the spinning cell and withdrawn through aspiration pipe 3. After emerging from the spinning cell, the yarn 8 is led through guide 18 and is passed through the bars 13 and 14, then through guide 20 and over guide rollers 16, 17, and 18 and wound on a suitable bobbin or sleeve 12. The bars 13 and 14 are attached to a crank shaker arm 11 which in turn is attached rigidly at 10

to a shaft 9. At the lower end of shaft 9 is connected an arm 15 having a slot 21 in which is movably mounted a pin 23 attached to a wheel 22. The wheel 22 is given an irregular motion by means of the motor 25 operating through a magnetic clutch 24 of the type described in the Patent No. 2,120,990 to Picard and Oriol. The circular motion of the pin 23 gives to the arm 15 a rocking motion, which in turn gives bars 13 and 14 a similar motion. Due to the fact that the rotation of the wheel 22 is irregular or at varying rates of speed (due to the magnetic clutch 24), the rocking motion of the bars 13 and 14 is also irregular, thus giving to the thread not only a variable denier, but also variations in denier at irregular or random intervals.

For convenience the invention has been described in terms of dry spinning a variable denier cellulose acetate yarn. Obviously, it is equally applicable to the dry spinning of an artificial variable denier yarn consisting of cellulose esters such as cellulose acetopropionate, cellulose propionate, or cellulose ethers such as methyl, ethyl, and benzyl cellulose, or polyvinyl alcohol and/or acetals and/or ester derivatives thereof or synthetic resins such as are disclosed in Carothers U. S. Patent No. 2,071,253.

The process of the invention makes possible, for the first time, a sharp transition from thick to thin portions in cellulose derivative threads. By this method it is possible to make in yarn having an average denier of 300, thick portions of less than three inches in length and have a maximum size at least 500 denier greater than the average, and in which the increase in size is at least 200 denier per cm. of yarn length. In addition to making possible the production of unique variable denier cellulose acetate yarn, the process of the invention offers the advantage of being substantially continuous in that yarn breaks are comparatively few and far between, possibly due to the fact that the yarn tends to be kept taut with respect to take-up members even though the ratio of extrusion speed to speed of withdrawal is varied.

Since it is obvious that many changes and modifications may be made in the above process as described without departure from the spirit and nature of the invention, it is to be understood the invention is not to be limited thereto except as set forth in the appended claims.

I claim:

1. The method of forming variable denier cellulose derivative yarn comprising extruding a cellulose derivative solution into a gaseous evaporating medium traveling in a direction countercurrent to the direction of extrusion throughout the region wherein the yarn is in a plastic state, and withdrawing said yarn through said gaseous

55 evaporating medium at a speed varying at times greater than the speed of extrusion thereby imparting abrupt variations in denier along the length of said yarn.

2. The method of forming variable denier cellulose acetate yarn comprising extruding a cellulose acetate solution into a gaseous evaporating medium traveling in a direction countercurrent to the direction of extrusion throughout the region wherein the yarn is in a plastic state, and withdrawing said yarn through said gaseous evaporating medium at a speed varying at times greater than the speed of extrusion thereby imparting abrupt variations in denier along the length of said yarn.

3. The method of forming variable denier cellulose

lose acetate yarn comprising extruding a cellulose acetate solution into a gaseous evaporating medium traveling in a direction countercurrent to the direction of extrusion throughout the region wherein the yarn is in a plastic state, and withdrawing said yarn through said gaseous evaporating medium at a speed varying at times greater than the speed of extrusion, the velocity of gaseous evaporating medium being at least 40 yards per minute and the speed of withdrawal of the yarn at least 100 yards per minute thereby imparting abrupt variations in denier along the length of said yarn.

4. The method of forming variable denier cellulose acetate yarn comprising extruding a cellulose acetate solution in a downward direction into a gaseous evaporating medium traveling in an upward direction throughout the region wherein the yarn is in a plastic state, and withdrawing said yarn through said gaseous evaporating medium at a speed varying at times greater than the speed of extrusion thereby imparting abrupt variations in denier along the length of said yarn.

5. The method of forming variable denier cellulose acetate yarn comprising extruding a cellulose acetate solution in a downward direction into a gaseous evaporating medium traveling in an upward direction throughout the region wherein the yarn is in a plastic state, and withdrawing said yarn through said gaseous evaporating me-

dium at a speed varying at times greater than the speed of extrusion, the velocity of gaseous evaporating medium being at least 60 yards per minute and the speed of withdrawal of the yarn at least 100 yards per minute thereby imparting abrupt variations in denier along the length of said yarn.

6. The method of continuously dry spinning artificial yarn to form a variable denier artificial yarn which comprises extruding a spinning solution into a gaseous evaporating medium traveling in a direction countercurrent to the direction of extrusion throughout the region wherein the yarn is in a plastic state, and withdrawing said yarn through said gaseous evaporating medium at a speed varying at times greater than the speed of extrusion thereby imparting abrupt variations in denier along the length of said yarn.

7. The method of continuously dry spinning superpolymer yarn to form a variable denier superpolymer yarn which comprises extruding a superpolymer spinning solution into a gaseous evaporating medium traveling in a direction countercurrent to the direction of extrusion throughout the region wherein the yarn is in a plastic state, and withdrawing said yarn through said gaseous evaporating medium at a speed varying at times greater than the speed of extrusion thereby imparting abrupt variations in denier along the length of said yarn.
